UNITED STATES PATENT OFFICE.

MARY PIERNON MITCHELL, OF EATON, OHIO.

INNER TUBE.

Application filed March 25, 1920. Serial No. 368,590.

To all whom it may concern:

Be it known that I, MARY PIERNON MITCHELL, a citizen of the United States, residing at Eaton, in the county of Preble and State of Ohio, have invented a new and useful Inner Tube, of which the following is a specification.

It is one object of this invention to provide an inflatable rubber inner tube for 10 pneumatic vehicle tires which will resist puncture.

Another object of the invention is to provide a tube of the kind mentioned which will not become pinched, due to cracks or other 15 irregularities in the tire casing.

The invention aims, further, to provide a novel reinforcement for an inner tube of the sort above alluded to.

It is within the province of the disclosure 20 to improve generally and to enhance the utility of devices of that type to which the invention appertains.

With the above and other objects in view, which will appear as the description proceeds, the invention resides in the combination 25 and arrangement of parts and in the details of construction hereinafter described and claimed, it being understood that, within the scope of what is claimed, changes in 30 the precise embodiment of the invention shown can be made without departing from the spirit of the invention.

In the accompanying drawings:

Figure 1 shows in transverse section, an 35 inner tube equipped with the reinforcement forming the subject matter of this application; Figure 2 is a detail enlarged from Figure 1; Figure 3 is a plan of the reinforcement, the same being laid flat; and Figure 4 is a diagrammatic cross section showing a modified form of the invention.

In carrying out the present invention, there is provided a reinforcement including 40 a piece of netting denoted by the numeral 1. Although any desired material may be used in the making of the netting, wire is preferred, and any kind of metal having the necessary characteristics, such as flexibility, 45 resiliency or strength may be employed. The netting preferably but not necessarily is cleaned in any desired way, such as by the application of benzine, gasoline, naphtha or the like, although, in practice, it may be found possible to clean the netting mechanically. The cleaning step may be dispensed 50 with, sometimes, but when the best possible

results are desired, the cleaning step is resorted to.

After the wire netting 1 has been cleaned, if it is considered desirable to clean the netting, cords 2 may or may not be incorporated in the netting. The cords may be made of cotton, linen or any other suitable substance, and are incorporated with the netting by threading them through the netting or by 60 weaving them into the netting along with the wires of the netting. It is to be understood distinctly that the cords 2 may be omitted if desired, but when they are used, they aid in holding the rubber on the netting, as will be explained hereinafter.

The netting 1 and the cord 2, if the cords are used, are treated with a vulcanizable cement. The cement may be worked into the meshes of the netting by means of a brush or swab, or by hand, or the netting may be dipped into the cement. It may be desirable to dip the netting into the cement repeatedly. After the netting has been treated 75 with cement, the cement is dried partially 80 or is permitted to dry.

This drying operation may be carried out in any desired way. In some instances, the netting is merely hung up and permitted to dry until the cement is tacky enough 85 to exercise its function without running or dripping. The netting is incorporated with one or more layers of rubber in any desired way. In some instances, the netting, 90 covered with the partially dried cement, is rolled into or upon the layer of rubber and the rubber may be coated with cement if desired. Again, as shown in the drawings, the netting is placed between layers 3 of 95 rubber, before the vulcanizable cement has dried completely, the rubber then being vulcanized, to form, with the netting, a unitary reinforcement.

The reinforcement, constructed as set forth, is introduced into the tread portion 100 of an inner tube 5, or is placed otherwise therein, as hereinafter explained. As indicated at 6, the reinforcement, in one form of the invention, does not extend entirely around the tube 5, transversely, one half of 105 the tube, more or less, considered transversely being devoid of the reinforcement. In any event, however, the tread portion of the tube is reinforced throughout such an area as is likely to be subjected to puncture. The reinforcement is flexible enough 110 so that it will not interfere materially with

the bending of the tube and since the reinforcement does not extend entirely around the tube, transversely the tube, obviously may expand. The reinforcement extends throughout the length of the tube considered circumferentially.

As depicted in Figure 4, one reinforcement 10 is placed in the tread of the tube 11, another reinforcement 12 being placed 10 in the inner portion of the tube. The reinforcements are spaced apart, along their longitudinal edges, sufficiently so that the tube may expand.

Refractory material, such as soapstone, or 15 asbestos is applied to the outer surface of the tube in any desired way. According to one method of procedure, the outer surface 20 of the tube may be covered thinly with cement and upon this cement, the asbestos 4 is placed. In alluding to asbestos, it is to be understood that an impalpable powder is not employed, the asbestos being merely the commercial bulk powdered asbestos which falls far short of being an impalpable powder. Asbestos need not be used, 25 but if it is employed, it serves to prevent the tube from heating, when the tube has frictional contact with respect to the tire casing.

30 It will be obvious that an inner tube for tires, constructed as above set forth, will be well adapted to withstand puncture and pinching, and will be strengthened and reinforced. It is well known that, if the inner 35 side of a tire casing is cracked slightly, or if the fabric fails, to a slight extent, not enough to produce a blowout, the inner tube, nevertheless, is often pinched and, after a short period bursts, tears or punc-

tures. Since the tube forming the subject 40 matter of this application is reinforced, the tube will not enter readily into small fissures in the inner surface of the casing and become pinched or damaged as aforesaid.

Having thus described the invention, what 45 I claim as new and desire to protect by Letters Patent of the United States is:—

1. An inner tube for vehicle tires, embodying a layer of wire netting coated with adhesive material which is partially dried 50 prior to the assembly of the tube.

2. An inner tube for vehicle tires, embodying a layer of wire netting coated with adhesive material which is dried to a point 55 of tacky adhesion prior to the assembly of the tube.

3. An inner tube for vehicle tires embodying layers of material which are treated with vulcanizable cement; and a layer of wire netting located between the 60 aforesaid layers, the layer of wire netting being coated with adhesive material which is dried to a point of tacky adhesion prior to the assembly of the tube.

4. An inner tube for vehicle tires, embodying a netting composed in part of metal and in part of cords, the netting being coated with adhesive material which is dried to a point of tacky adhesion prior 65 to the assembly of the tube.

In testimony that I claim the foregoing as my own, I have hereto affixed my signature in the presence of two witnesses.

MARY PIERSON MITCHELL.
